UNITED STATES PATENT OFFICE.

HERMANN HILDEBRANDT, OF HAMBURG, GERMANY.

COMMINUTING AND MIXING OF SUBSTANCES OF ALL KINDS.

Application filed June 1, 1925, Serial No. 34,159, and in Germany May 26, 1924.

It has been heretofore proposed to use the centrifugal force of balls for the extreme comminution of substances; but in such process the balls and the material were raised or carried through the movable grinding path without, however, accomplishing a maximum degree of grinding action.

According to the present invention, the grinding action is increased by causing the balls and the material to positively traverse a path which is different from the rotational direction of the movable grinding element. The motion which is achieved thereby gives the comminuting means, for instance, balls 15 on the movable grinding surface a maximum of movement energy so that the balls can follow the rotational velocity of the grinding path in practically every case.

The invention consists further in that the 20 comminuting means together with the material to be treated are moved constantly in a closed circuit by centrifugal force, over one or more movable grinding surfaces and over one or more stationary grinding surfaces, whereby the direction of movement 25 of the current of balls and material on the movable grinding surface is different from the direction of movement of the latter and the balls are driven over surfaces or guide 30 paths of a closed work chamber.

An apparatus for carrying out this process comprises guide paths formed by the arrangement of steep walled shell-formed, 35 movable grinding elements in combination with stationary grinding elements.

The comminuting means and the material, on passage from one grinding surface to the other, may be subjected to an impact action, and likewise the section and number of 40 the movable and stationary grinding paths may be modified relatively. The arrangement of the movable and the rigid or stationary grinding elements with respect to each other is, as shown for example in the 45 accompanying drawings and explained in greater detail in the specification, so formed that guide paths for the current of balls and material is produced, which can be further supplemented by guide elements for causing 50 an impact or drop action. The walls of the guide paths are preferably equally spaced apart throughout, except for the in and outlet points for the current of balls and

material. The balls are received by the under side of the movable grinding member, 55 are set in rotation and rise together with the material up the steep walled movable grinding element, leaving the latter at the highest point and passing to the stationary grinding element. From here they again 60 pass to the lowermost point of the movable grinding element. The stationary grinding element may be arranged outside or inside the movable element. With the arrangement of several grinding elements the technical or practical possibilities of the assemblage of the individual features of the present invention are immediately apparent, so that any combination comprising the main feature of the invention falls within it. 70 Also the chambers which serve for the impact action of the balls at the point of passage from one grinding element to the other may be in any number, and their relative 75 positions modified as desired.

Various substances can be mixed together in the same way.

The apparatus is illustrated in the accompanying drawings in which:

Figure 1 is a vertical sectional view of 80 one form of the invention.

Fig. 2 is a similar view of a modification of a detail of the structure shown in Fig. 1.

Fig. 3 is a top plan view of the slotted 85 plate shown in Fig. 2.

Fig. 4 is a vertical sectional view of a modified form of machine.

Fig. 5 is a detail sectional view taken on line A—B of Fig. 4.

Fig. 6 is a fragmentary vertical sectional 90 view of another modification.

Fig. 7 is a similar view of another form of invention.

Fig. 8 is a vertical sectional view of another embodiment of invention.

Fig. 9 is a sectional view of a portion of the machine shown in Fig. 8 taken on the line C—D of that figure.

Figs. 10 and 11 are vertical sectional views 100 of other forms of the invention.

In the devices illustrated in Figures 1 to 6 (Sheets 1 to 3) the balls and the material for example are contained in circulating guiding and pressure chambers formed for example by one or more deep rotary shells, an outer stationary grinding track 105

and an inner stationary guiding body suspended in the rotary shell.

By the rotation of the shell the layers of balls located in the guiding and pressure chamber, and the material between them are carried round by the shell by reason of gravitational and centrifugal pressure friction and moved at a high peripheral speed and tend to pass along the steep shell wall.

10 It is however not possible for them to do this until their centrifugal force in the guiding and pressure chamber has reached such a value that it can overcome the frictional pressure and the weight of the layers of balls located above the rotating shell on the grinding track and in the grinding chamber between the grinding track and the guide body.

In this manner the balls are driven over 20 the grinding track whereby the balls comminute by centrifugal force the material which moves with them, and in accordance with the shape of the upper grinding chamber and the stationary guiding bodies are 25 conducted away from the grinding track inwardly towards the middle and downwardly upon the rotating shell, whereby they are projected on the upper wall of the stationary guiding body by the pressure of the balls following on the rotating shell in the guide and pressure chamber or 30 by the energy of rotation of the balls rotating on the grinding track, or after destroying 35 the centrifugal energy of the balls rotating on the stationary grinding track fall on the wall of the guide body, further comminuting the material which moves therewith and after destroying the energy of 40 movement pass from the upper wall of the guide body through openings in the stationary guide body to the middle of the rotary shell and here again comminute the material by impact action.

When reaching the rotating shell the 45 balls, with the material between them, have centrifugal force again imparted thereto and the layers of balls close up at the bottom and thus effect by this continuous additional increase in pressure in the guide and pressure chamber, a continuous pressing out of the balls and the material from the upper grinding track and a continuous circulation in the mill.

50 The material is continuously between the balls and partakes of the continuous movements thereof whereby the material is mainly comminuted by impact and friction action of the balls on the grinding track, on the guide body, and on the bottom of the shell.

55 By means of the device illustrated in Figure 7 (Sheet 3) the balls and the material, in a similar manner as described in connection 60 with the devices in Figures 1 to 6, are driven upwardly continuously from the ro-

tating shell and also have a grinding movement imparted thereto by reason of the guide members or guide ribs provided at the lower surface of the stationary suspended guide bodies, leading to the rotating shell, and comminute the material between the balls.

65 In the device illustrated in Figures 8 and 9 on Sheet 4, the balls and the material have a high peripheral speed continuously imparted thereto by a deep rotating shell, which either with a shell, open at the bottom and top, and inserted therein and rotating therewith or suspended therein and stationary, may form a guiding and pressure chamber, by reason of the high bearing pressure against the steep shell wall resulting from centrifugal force and guided 80 upwardly and driven over a stationary grinding track, from which the balls and the material by means of the energy of rotation are projected by projecting ribs on the grinding track downwardly directly to a suitable point of the rotating shell or on the upper wall of the suspended stationary 85 guiding body and from here are passed through a central opening to the middle of the rotating shell and thus mainly by the impact action when the balls strike the wall of the rotating shell or the stationary guiding bodies together with the diverting pressure comminute the material which moves therewith.

90 In the devices illustrated in Figures 10 and 11 on Sheets 5 and 6, the balls and the material have imparted thereto a high peripheral speed and the absolute speed of the rotating shell by means of rotary shells open at the bottom and at the top and gradually enlarged towards the top and arranged around the shaft and secured thereto, by reason of the gravitational friction and the friction due to centrifugal pressure, and by 95 reason of the centrifugal force thus obtained are continuously guided from the bottom to the top and projected with the projecting force suitable for every kind of material on the stationary grinding track which surrounds the rotating shell at predetermined 100 distances, from where the balls and the material by reason of the energy of rotation remaining on the grinding track or by gravity are conducted or fall into the stationary casing shell surrounding the rotating shell at predetermined intervals, and from the casing shell bottom are pressed and guided by means of the column of balls above them upwardly on the guide body arranged centrally in the casing shell bottom and through the lower inlet openings 105 of the rotating shells to the inner surfaces thereof or to the guiding chambers thereof, and from here they are driven upwardly and projected on to the grinding track in a 110 continuous stream by reason of the friction 115

and the centrifugal force on the rotating shells, and the balls by reason of the impact action continuously comminute the material carried along by the balls and projected on the grinding track.

By these new devices it has become possible to impart to a large number of small balls with the material between them a high peripheral speed and a high projecting force resulting therefrom when striking the grinding track on which the material is broken up or comminuted, and at the same time to set the balls and the material into a continuous flowing movement and to retain this continuously and then to conduct them continuously over the stationary grinding path whilst beating thereon or frictionally engaging therewith, whereby a continuous operation is produced in the mill and the sufficiently fine dry material is continuously withdrawn from the mill through the flowing energy of a flowing medium through upper openings and the wet material is periodically emptied through lower openings and the supply of all the material is effected through upper openings.

In the device according to Figure 1, Sheet 1, there is secured to a vertical shaft 1 a deep rotating shell 2, freely supported at the top which is closed at the bottom and open at the top into which a number of similar shells 2 rotating therewith and open at the top and bottom can be inserted in such a manner that between them are formed free guiding and pressure chambers, preferably all arranged at the same distance apart, for guiding one or more layers of balls and material. The inserted rotary shells open at the top and bottom are preferably secured to the outer shell by means of distance pieces and securing elements.

These rotary shells 2, a stationary grinding track 3, and a stationary suspended guide body 4, form annular chambers 5 and 6 in which are contained the grinding bodies 7 and the material. The guide body 4 is of such a shape and so arranged that its lower wall is similar to the adjacent wall of the rotary shell 2 and thus is every where at the same distance from the rotating shell and this distance is such that in the guiding and pressure chambers thus formed, one or more layers of balls and the material can have a high peripheral speed and centrifugal force imparted thereto and be driven upwardly by the gravitational and centrifugal pressure on the rotating shell.

By rotating the deep shells 2 the balls and the material in the guiding and pressure chambers 5 tend to move outwardly and upwardly, but can only pass upwardly into the grinding chamber 6 when the upwardly acting pressure of the ball's rotating on the rotating shell and to which centrifugal force has been imparted, has become

so great that it can overcome the centrifugal energy, the weight and the friction of the whole column of balls rotating more slowly on the grinding track 3 and in the grinding chamber 6. By increasing the 70 rotating shell the guiding and pressure chambers are increased whereby the balls and materials set in rotation and to which centrifugal force is imparted, and thus also the comminuting action can be increased. 75

By reason of the centrifugal force the balls exert a very high pressure outwardly on the shells and grinding track and upon one another by which the material, which is between the balls and continually moves therewith, is energetically comminuted. 80

Towards the top the speed of rotation of the balls in their almost horizontal track which passes upwardly is reduced by reason of the grinding operation which is carried out on the stationary grinding track. 85

The balls and the material cannot return in the narrow chambers 5 and 6 but are gradually driven upwards by the pressure of the succeeding balls and material in the grinding and pressure chamber 5 until finally, by reason of the stopping of the guide body 4 in the upper part of the grinding chamber 6, leave the inner side of their guide and are thus forced or projected or fall towards the middle on the upper wall of the guide body 4, whereby they further comminute the material on the wall of the stationary suspended guide body when beating open this by impact and on further rotation by friction. 90

The balls and material finally fall from the upper wall of the guide body through a central opening 8 in the guide body on the lowest point of the rotating shell, comminuting the material by an impact action. Here they again begin to rotate, connect up with the layers of balls in the guiding and pressure chamber 5 at the bottom thereof and thus increase the pressure thereof upwardly whereby as many balls are again pressed out of the grinding chamber 6 towards the interior. 105

When using the above-described guiding and pressure chamber it would not be possible to return the balls and the material carried therewith towards the interior and to the middle of the shell as they would be always forced outwardly by centrifugal force and towards the largest diameter and it is only by the above described method of guiding that they can be returned towards the interior and towards the bottom to the middle of the rotating shell. 115

The arrangement of guide ribs or guide bodies on the inner surface of the grinding track also enables the balls and the material to be thrown or returned to the middle of the shell and to the bottom by reason of the energy of rotation which they still re- 120 125 130

tain from the grinding track, or when striking on the raised portions of the grinding track are caused by the elasticity of the balls to jump from the grinding track and 5 fall towards the middle of the rotating shell.

The wedge-shaped annular slot 9 formed between the rotating shell 2 and the stationary grinding track 3 is closed by a wedge ring 10, adjustable from the outside, in 10 such a manner that the centrifugal force acting therein towards the guiding chamber will force any material which has entered the slot back into the guiding chamber.

For supporting this action there is also 15 provided a blade ring 11, secured to the rotating shell 2, of which the blades produce an air pressure in the chamber 12 so that any material which may have entered the slot, will be thrown back by the air pressure into the grinding chamber.

The guiding body 4 is secured to the casing cover 15 centrally by means of ribs 13 and bolts 14, whereby the cooling and heating liquids are conducted to the hollow 25 guide body through passages in the bolts 14 and ribs 13. In the casing cover is provided a discharge opening 16 and an opening 17 through which the most finely ground dry material can be withdrawn from the 30 guiding chamber through a flow medium.

The discharge of the fine material is effected, in so far as dusty particles are not withdrawn from the bottom, through a discharge opening arranged centrally at the 35 lowest part of the rotating shell 2, which is opened and closed by an axially movable discharge plunger 18. For discharge the plunger is lowered by the spindle 19 by means of the toothed wheels 20 whereby 40 the material passes through the aperture formed between the plunger 18 and the packing plate 21 into the discharge chamber 23 and from here is projected through the holes 24 into the withdrawal chamber 45 25. The plunger 18 can also be pressed against the packing plate by spring action.

The discharge slot 22 is much smaller than the balls so that these continue to rotate without interruption.

The packing plate 21 may also be provided with longitudinal slots 22 as shown in Figures 2 and 3, which are closed by suitably raised portions on the discharge plunger.

In the device according to Figures 4 and 5, Sheet 2, the uniform distance of the stationary suspended guide body 4 from the rotating shell 2 is so large that a number of rows of balls and layers of balls have room 50 side by side whereby the guiding and pressure chamber 5 becomes greater and the grinding action on the grinding track and also between the separate balls becomes 55 more intense. The same result will be obtained by enlarging the distance between

the shells open at the bottom and at the top and fitted within the lower rotating shell with which they rotate.

In order to impart to the balls in the guiding chamber a more intense grinding 70 action and also to return them more rapidly to the centre of the shell, the stationary grinding track 3 and the stationary guiding body 4, the latter, however, only on the upper wall, may be provided with guide 75 ribs 26 which are arranged transversely or at an angle to the direction of the movement of the balls.

In the device according to Fig. 6, Sheet 3, the slot 9 extends upwardly. In this 80 manner particles of material which pass into the slot 9 are conducted back to the grinding chamber also by gravity in addition to the centrifugal force and the compressed air which is produced by means of 85 the blades 11 secured to the shell. By reason of the upwardly drawn shape of the grinding chamber 6, not only the grinding surfaces, but also the fall in height over the balls and thus the impact action for comminuting the material on the shell bottom are increased.

The cooling or heating of the rotating shell is effected by a liquid which is applied to the outer rotating shell wall by a nozzle 95 ring 27 and by a blade ring secured to the rotating shell, and rises upwardly thereof by reason of centrifugal force, whereby the liquid is prevented from being thrown off too early by the hood 28. At the largest 100 diameter the liquid is thrown off and conducted away at the opening 29.

The upper outflow opening 17 for the dry material and the inlet opening 16 for all the material are in this case arranged centrally.

In the device according to Fig. 7, Sheet 3, the stationary guiding body is provided on its side turned towards the rotating shell with guide bars or guide ribs extending up 110 to the shell which may be arranged vertically or at an angle in relation to the path of the balls, whereby the balls have a rolling and grinding movement imparted thereto when moving up the rotating shell.

In the devices according to Figures 8 and 9, Sheet 4, projecting ribs 31 are provided on the stationary grinding track 3, which are of such a curvature that the balls and the material can be projected substantially horizontally from the upwardly directed track in any suitable direction by reason of the energy of rotation. The projecting ribs 31 are either formed integral with the grinding track 3 or inserted therein as 120 a separate part whereby they may be formed hollow and arranged so as to be cooled or heated.

The devices according to Figures 10 and 11, Sheets 5 and 6, only differ from the 130

previous devices therein that in these devices the grinding operation is mainly effected by impact action and wherein the balls and the material after beating upon the grinding track fall downwardly outside the rotating shell into a stationary casing shell surrounding the rotating shell at a predetermined distance therefrom, and here are forced upwardly and guided by the pressure of the column of balls lying above them to the lower opening of the rotating shell on to a guiding body arranged centrally in the bottom casing shell.

A rotating shell 2 is secured to a vertical shaft 1 by distance pieces 32, the shell being open at the bottom and at the top, and being gradually enlarged towards the top. In this shell are contained the balls and the material. By gravitational and centrifugal friction they are driven by the rotating shell 2, have a high peripheral speed and centrifugal force imparted thereto by this and are driven upwardly. At the upper edge they pass outwardly from the shell and by impact action strike upon the grinding track 3, arranged outside, whereby the main grinding operation is effected. Whilst moving spirally or falling and carrying out a further grinding operation the balls and the material by reason of their gravity move downwardly and collect in the bottom of the casing shell 33. They gradually heap up and thus by their weight force out the balls and the material lying in the middle of the casing shell around the guiding body combined with the discharge plunger 34 and projecting into the grinding chamber or into the lower opening of the rotating shell, so that they again come within reach of the inner surfaces of the rotating shell 2 and are caused to rotate with the rotating shell by friction whereby the operation is recommended. In these devices the slot 9 lies in the direction of the ball track so that an outflow of the material at this point is not possible.

The rotating shell 2 is closed towards the collecting chamber in the casing shell 35 so as to prevent any deleterious friction with the balls and material, by a stationary protecting shell 36.

The protecting shell 36 is suspended and secured in the larger casing shell which surrounds the protecting shell at suitable distances therefrom, by means of distance pieces thus forming the guiding and pressure chamber for guiding the balls and material downwardly. The slots 37 and 38 formed between the rotating shell 2 and the stationary protecting shell 36 are located in the operating chamber and therefore do not lead to any losses.

Any material which may enter the chamber 39 formed by the rotating shell 2 and the stationary protecting shell 36 is again

moved upwardly into the guiding chamber by the fan blades 40. With a sufficiently large annular space between the stationary casing shell 33 and the rotary shell 2 the stationary protecting shell 36 may also be omitted.

The raising of the securing elements for the rotary shells to the hub of the shaft enables the lower part of the rotating shells 2 to be made flat and smooth and thus the driving of the balls and material is facilitated a total weight thereof is brought into play for producing the friction so that they will be caused to rotate more rapidly with the shells.

In the device shown in Fig. 11, Sheet 6, a number of rotating shells are placed everywhere at uniform distances one from the other and secured upon a common shaft for guiding one or more layers of balls and material upwardly.

The discharge of the fluid material is then effected downwardly through a discharge opening arranged centrally or laterally at the bottom at the deepest part of the casing shell and closed by means of axially movable discharge plunger 34. The packing surfaces of the discharge opening in the casing shell 33 and of the discharge plunger 34 are conical.

The withdrawal of the dry dust-like material is effected through the hollow shaft or through the hollow hub upwardly.

The charging is effected through a pipe 41 suspended centrally in the top of the hollow shaft.

All the stationary and rotary shells and the grinding tracks according to the devices in Figs. 1 to 11 can be cooled or heated. All the parts exposed to wear can be fitted with armouring which can be rapidly replaced.

As grinding bodies it is possible to use balls or otherwise shaped bodies of the same or different sizes and of the same or different material so that when using balls of different sizes these according to their larger or smaller mass can be driven more rapidly by reason of the gravitational and centrifugal pressure friction and are driven forwardly more rapidly by the centrifugal force and thus assist in producing relative friction between the balls and this friction, when using grinding or mixing bodies of different materials, by reason of the different co-efficients of friction between, for example, spherical grinding and mixing bodies, is increased and thus the comminution or mixing of the material is supported.

The above described devices can also be used for mixing various substances with or without the addition of pressure, vacuum, temperature or electric discharges.

The comminuting process for comminuting up to colloidal fineness can be effected

with the assistance of protecting colloids and the mixing process with the assistance of agents accelerating the mixing or the emulsifying.

5. Having thus described my invention what I claim as new and desire to secure by Letters Patent is:—

1. An apparatus for comminuting and mixing materials up to a colloidal degree of 10 fineness comprising an enclosed operating chamber, at least one stationary grinding track and at least one guide passage arranged in the chamber, comminuting means arranged in the chamber, and at least one 15 impelling means for moving said comminuting means together with material to be treated constantly in a continuous stream, by centrifugal action over the stationary grinding track and through said guide passages.

2. An apparatus for comminuting material to a colloidal degree of fineness and admixing the same comprising a rotatable substantially parabolic grinding surface, a 25 complementary shaped stationary grinding surface spaced from the first mentioned grinding surface to provide a guiding path extending upwardly and outwardly from the axis of the rotatable surface, an annular 30 stationary grinding surface arranged at the upper end of said path, and guiding means arranged to direct grinding elements and the material under-going grinding from the stationary annular surface to the lower portion 35 of the first mentioned grinding surface.

3. An apparatus as claimed in claim 2 in which the guiding means directs the grinding elements and material first in a horizontal direction and then downwardly.

40. 4. An apparatus as claimed in claim 2 in which the guiding means includes a substantially horizontal surface provided with impact and guide ribs extending into close proximity to said annular guiding surface.

5. An apparatus as claimed in claim 2 in which the annular guiding surface is provided with ribs for directing the grinding elements and the material into the guiding means.

6. An apparatus as claimed in claim 2 in which the first mentioned grinding surface terminates at its lower portion in a substantially horizontal unbroken surface.

7. An apparatus as claimed in claim 2 in 55 which the first mentioned grinding surface is formed on a rotatable pan, and a substantially parabolic hollow member mounted on said pan within the latter and spaced from the pan to permit the grinding elements and 60 material to move upwardly and outwardly between said hollow member and the pan under the centrifugal force developed by the pan.

8. An apparatus as claimed in claim 2 in 65 which the guiding means includes a sleeve

extending into the space formed by said substantially parabolic grinding surfaces.

9. An apparatus as claimed in claim 2 in which the substantially parabolic rotatable grinding surface is formed in a rotatable 70 pan, said pan having an opening at its lower end, and a plunger normally closing said opening.

10. An apparatus as claimed in claim 2 in which the stationary substantially parabolic surface is formed on a hollow suspended member and means for introducing a 75 temperature changing medium into and out of said hollow member.

11. An apparatus as claimed in claim 2 in which the rotatable substantially parabolic grinding surface terminates adjacent to the annular grinding surface, said surfaces being separated by an annular space 80 wedge shaped vertically.

12. An apparatus as claimed in claim 2 in which a wedge-shaped opening is provided between the rotatable grinding surface and the annular grinding surface, and a rotatable 85 fan for preventing material from discharging through said opening.

13. An apparatus as claimed in claim 2 including means for cooling or heating one of the grinding surfaces.

14. A process as claimed in claim 1, characterized in that an intensely energetic movement is imparted to the comminuting means by a rotatable element and thereby the comminuting means describes a spiral movement over the movable surface and then 90 return over a second stationary grinding surface to the guide path.

15. An apparatus as claimed in claim 1 in which the impelling means include at least one movable track for the comminuting means, said impelling means being adapted 105 to cause the comminuting means to carry out a substantially spiral co-relative movement on the sphere of the movable track, and to return over the stationary grinding track 110 to the movable track.

16. An apparatus as claimed in claim 1 including at least one impact surface, and another passageway for feeding the comminuting means and material undergoing treatment from said guide passages to the impact surface.

17. A device for comminuting and mixing materials up to a degree of colloidal fineness including a closed working chamber 120 formed by a stationary grinding track and an annular movable grinding track, and comminuting means movable over said tracks by centrifugal force exerted by the movable track.

18. A device as claimed in claim 17 in which the movable grinding track is provided with an annular inclined surface arranged adjacent to a similar surface on the chamber, said surfaces being directly oppo- 125

site one another and being inclined in the direction in which the comminuting means moves, so as to prevent fine material from passing out of the chamber between said surfaces.

19. A device as claimed in claim 17 in which the movable track and a stationary wall of the chamber are provided with adjacent inclined annular surfaces forming an annular space leading into the chamber,

said surfaces being arranged in the direction of flow of the comminuting means so as to prevent material from the chamber discharging through said opening, and a pressure chamber communicating with said opening for feeding a gaseous medium into the closed chamber. 15

In testimony whereof I affix my signature.

HERMANN HILDEBRANDT.
